Attn:

UNITED STATES PATENT OFFICE

164,239

COMMERCIAL ELECTRIC BAKING AND ROASTING OVEN

Sam Horwitz, Chicago, Ill.

Application May 14, 1951, Serial No. 15,172

Term of patent 14 years

(Cl. D81—4)

To all whom it may concern:

Be it known that I, Sam Horwitz, a citizen of the United States, residing in Chicago, Cook County, Illinois, having invented a new, original, and ornamental Design for a Commercial Electric Baking and Roasting Oven, of which the following is a specification, reference being had to the accompanying drawings, forming a part hereof, and in which drawings—

Figure 1 is a perspective view of a commercial electric baking and roasting oven embodying my new design; and

Figure 2 is a side view thereof.

The other side of the oven, not shown, is substantially like the side shown.

I claim:

The ornamental design for a commercial electric baking and roasting oven, substantially as shown and described.

SAM HORWITZ.
